UNITED STATES PATENT OFFICE

HERMAN JOHN HERFORT, OF PATERSON, NEW JERSEY

MULCH-PAPER-LAYING MACHINE

Application filed July 2, 1929. Serial No. 375,381.

This invention appertains to new and useful improvements in machines for laying mulch paper upon the ground for protecting plants and various growths.

5 The principal object of this invention is to provide a machine for laying mulch paper upon the ground in a manner whereby the paper will be prevented from blowing away.

Another important object of the invention 10 is to provide a machine for laying mulch paper upon the ground in an even and neat appearing manner. These and numerous other important objects and advantages of the invention will become more apparent to 15 the reader after considering the invention as described and claimed hereinafter.

In the drawings:

Figure 1 represents a top plan view of the improved machine.

20 Figure 2 represents a side elevation in partial longitudinal section.

Figure 3 represents an end elevation of the improved machine.

25 Figure 4 represents a fragmentary sectional view.

Figure 5 represents a vertical transverse sectional view.

Figure 6 represents an end elevation of the machine looking at the machine from the end 30 opposite to that shown in Figure 3.

Figure 7 represents a vertical sectional view through the paper after having been laid.

35 Referring to the drawings wherein like numerals designate like parts, it will be seen that the improved machine consists in construction of a pair of side boards 5-5. A cross board 6 is supported at one end of the machine upon the side boards 5-5 and its 40 end portions are adapted to project beyond the side boards in the manner shown in Figure 5.

At the forward ends of the sideboards 5 shovels 7 are supported by brackets 8 and 45 these shovels serve to cut furrows in the ground, in the manner shown in Figure 1. At the ends of the side boards 5-5 adjacent the shovel 7 is a roll 9 of mulch paper through which a bar 10 is disposed. The bar rests in 50 notches at the upper edges of the sideboards

5-5 and the paper strip is to be payed from the roll 9 and trained beneath the spool 11 interposed between the side boards 5-5 adjacent the rear end of the machine.

The spool 11 is mounted upon the shaft 12, 55 which shaft has its ends journaled in the sideboards 5-5. The spool 11 is cylindrical throughout its intermediate portion and is provided with outwardly flared heads or circumferential tapered flanges 13 at its ends.

On the end of each side bar 5 adjacent the spool 11 is a bracket 14 for supporting a disc 15 which disc serves to fill in the furrow previously excavated by the corresponding front shovel 7.

Whereas the rear end of the machine is supported by the roll 11, the forward end of the machine rides upon wheels 16 journaled to the bracket 17. A pull bar 18 is connected to the machine by the crankshaft 19. Secured upon the board 6 and at its intermediacy are knuckles 20 through which a pin 21 is disposed. The pin 21 extends through one end of a bar 22, which forms an element of the adjacent row marker. 75

This marker has its free end provided with a pivotally mounted leg 23 which can be secured in a position perpendicular with respect to the ground by a brace member 24. The leg 23 as well as the bar 22 may be swung 80 from one side of the machine to the other side where it is positioned to abut the adjacent stop lug 25.

It will thus be seen that as the machine is drawn along the ground, the front shovel 7 85 will dig furrows in the ground as substantially shown in Figure 1, simultaneously with the paying off of the mulch paper strip. The edge portion of the strip will overlie the furrows and the bevelled or outwardly flaring 90 heads 13 of the spool 11 will force the edge portions down into the furrows, after which the disc 15 will fill in the furrows so as to firmly retain the mulch strip upon the ground. While this operation is taking place, the leg 95 23 is drawing a line adjacent and parallel to the said furrows so as to indicate a guide for the next laying of mulch strip.

While the foregoing description has been couched in specific terms, it is to be under- 100

stood that numerous changes in the shape, size and materials may be resorted to without departing from the spirit and scope of the invention as claimed hereinafter.

Having thus described my invention, what I claim as new is:

In a machine of the character described comprising a wheeled frame, a spool mounted upon the same for supporting a roll of mulch paper, furrow diggers at the forward end of the frame, means for depressing the edge portions of the paper into said furrows, and means for filling in said furrows after the paper is laid, said depressing means comprising a spool of uniform diameter throughout its intermediate portion and having circumferential tapered flanges at its ends extending into the furrows formed by the diggers and adapted to engage the marginal edge portions of said paper for pressing them into the furrow.

In testimony whereof I affix my signature.

HERMAN JOHN HERFORT.
